POWER GENERATING APPARATUS

Charles W. Dake, Grand Haven, Mich.

Application June 30, 1936, Serial No. 88,258

15 Claims.

(Cl. 60—62.5)

My present invention relates to improvements in power generation and particularly to a sound wave operable apparatus including a motor and mechanism or method by which is utilized sound waves or impulses in the generation of mechanical power for operating mechanical devices such as sewing machines, pumps, electric dynamos and other mechanisms that may be driven or operated by mechanical power; and the objects of invention are, first, to provide an apparatus and system or method for utilizing the force of sound waves or impulses to drive mechanical devices and mechanisms; second, to provide an apparatus that will operate in conjunction with radio reception systems for the generating of mechanical power; third, to provide an apparatus and method for converting sound waves or impulses into mechanical movement; fourth, to provide a motor that will operate to drive mechanical devices by the force of sound waves or impulses, and, fifth, to provide a motor that will operate by sound cheaply.

I attain the above named objects and others that will appear from a perusal of the following description taken in connection with the accompanying drawings, in which—

Figure 1 is an external plan view of the apparatus and a portion of the electrical impulse receiving circuit shown diagrammatically.

Figure 2 is a sectional view taken on line 50—50 of Figure 1.

Figure 3 is a side elevation of the apparatus.

Figure 4 is a view looking into the motor portion of the apparatus as when the cover is removed.

Figure 5 is a view illustrating the arrangement of the motor shaft, sound operated diaphragms and speed or vibration control assembly, and

Figure 6 is an illustration of one form of member by which the speed of the motor and vibrations of the diaphragms are controlled.

Throughout the drawings and description, similar parts are designated by similar numerals, and referring thereto:

Numeral 1 represents the sound driven motor housing provided with front enclosing cover 2, 3 sound producer housing connected to the sound motor housing by sound directing frame 4 by the screws 5. At the under side of the sound producer housing 3 are feet 6 by which the housings 1, 3 and frame 4 together with their associated parts are supported. 7 represents diagrammatically a portion of the electromagnetic impulse receiving and amplifying circuit by which the electromagnetic impulses are received

from the atmosphere; circuit 7 may be of any form capable of receiving and amplifying radio impulses.

Within the sound producing housing 3 is loud speaker field coil 8 surrounding the core 9 and having, extending therefrom to connect the field coil 8 with the electromagnetic impulse receiving circuit, lead wires 10 and 11. Also surrounding the core 9, adjacent the field coil 8, is voice coil 12 connected to the electromagnetic impulse receiving circuit by lead wires 13 and 14. Extending from the front of core 9 to the sound producing housing 3 is sound conducting cone 15 secured in position by being clamped in the joint 16 between the sound producing housing 3 and the sound directing frame 4.

Within the motor housing 1 is mounted drive shaft 17 rotatable in ball bearings 18 supported in bores 19 at each end of the motor housing and retained therein by caps 20 secured by screws 21 and, intermediate the bearings 18 and permanently secured to the shaft 17 are shown driving ratchet wheels 22 engaged by pluralities of springable hardened steel pins 23, each of individual length, and attached at one of their ends to diaphragms 24 which span openings 25 extending through wall 26 of the motor housing 1. Screws 27 at the peripheral edges of the diaphragms 24 secure them in place. At one end of the shaft 17 is drive pulley 28 whereby power 30 is transmitted to the drive shaft by reason of vibration of the diaphragm can be transmitted from the shaft 17 to a driven device or machine.

Extending longitudinally of the motor shaft and in spaced relation thereto, within the motor 35 housing 1 is motor speed control shaft 29 having secured thereto diaphragm vibration dampening levers 30 having at their diaphragm contacting ends yieldable cushion pads 31. At one end of the speed control shaft 29 and secured thereto for 40 turning the same to contact the diaphragms 24 is lever 32 which may be manually operated to control the vibrations of the several diaphragms or connected to a speed control governor (not shown) which is operated by the motor.

Sound deadening insulation 33 is provided within the motor housing between the plates 34 and the walls of the housing. Sound deadening plate 35 extends throughout the entire area of the cover 2 and is clamped by the cover to the housing.

At the back of the sound producing housing 3 is removable plate 36 closing opening 37 through which the interior of the sound producing housing can be inspected.

55

- It is well known that electromagnetic impulses discharged from a suitable generating apparatus will travel great distances and there may be intercepted by any suitable antenna and thereby generate bi-directional electric currents to control and modify the plate current in a suitable receiving apparatus and which current is utilized to operate a sound producer or a so-called loud speaker. It is with the waves or impulses of this 5 produced sound as well as other sound that my present invention is concerned for the conversion of such sound waves into so-called horse power and referring to the operation of my present invention in its preferred form.
- 10 Electromagnetic impulses discharged into the atmosphere by a source such as the radio sending or broadcasting apparatus, will cut or thread through the antenna which may extend from a radio receiving apparatus and thereby generate in the antenna feeble or weak electric currents which may be amplified by the receiving apparatus to provide electric currents of higher magnitude or intensity than the currents generated in the antenna and these higher magnitude or 15 intensity currents transmitted to the loud speaker where because of the rapid change in magnitude of the electrical impulses in the coils of the loud speaker rapid magnetic vibration is set up in its core and thereby generate sound of different wave lengths or magnitude which are transmitted through the sound directing frame 4 to the diaphragms of the motor which diaphragms vibrate in accordance with the sound waves impinging thereon and in turn cause the shown springable pins connected to the diaphragms to vibrate longitudinally with the vibrations of the diaphragms and because of the pins engagement with the teeth of the ratchet wheels on the drive shaft will cause the drive shaft to rotate at high speed by 20 reason of the rapidity and force of diaphragms vibration caused by the rapidity and magnitude of the sound waves.
- It is to be understood that in the operation of my invention direct from sound waves produced by means other than the electromagnetic sound producer hereinbefore referred to, the electromagnetic sound producer and its casing 3 may be removed so that the sound waves emanating from some other source can impinge directly on 25 the diaphragms to which the springable steel pins engaging the ratchet wheels are attached and thereby vibrate the diaphragms in accordance with the magnitude and frequency of such sound waves.
- 30 Although my present invention has been described with particular reference to operation by sound waves produced by radio electromagnetic discharge, it is to be understood that the invention is equally operable by sound waves derived from any source and of sufficient magnitude and frequency. While I have shown and described springable pins connected to the diaphragms for engaging ratchet wheels for driving the drive shaft when the diaphragms are 35 vibrated, it is to be understood that any suitable means associated with the diaphragms and drive shaft may be employed to drive the said shaft by the vibration of the diaphragms.
- 40 Having described the invention, I claim:
- 70 1. In a power generating apparatus comprising an electromagnetic impulse receiving circuit and means for converting the said impulses received by said circuit into sound, a hollow housing enclosing the said means for converting electric magnetic impulses into sound, a hollow motor housing secured to the first named housing and having a division wall therein, the said division wall provided with a plurality of openings through it and vibratory diaphragms closing the said openings and secured to the said division wall adjacent the periphery of the said openings, each of said diaphragms having secured to one of its sides and extending transversely therefrom a plurality of independently springable pins of different lengths, a drive shaft rotatably mounted in the said motor housing and extending through one of its sides, a plurality of toothed ratchet wheels secured to the said drive shaft in spaced apart relation within the housing engaged by the said springable pins whereby the said ratchet wheels will be rotated by said springable pins when the said diaphragms are vibrated and a diaphragm vibration control shaft extending substantially parallel with the axis of said drive shaft and having secured to the diaphragm vibration control shaft a plurality of diaphragm vibration control levers and means for turning the said diaphragm vibration control shaft for pressing said vibration control levers against the said diaphragms, all for the purpose specified.
2. In a power generating apparatus comprising an impulse receiving circuit including means for producing and intensifying sound, and a housing for the said sound producing and intensifying means, a motor housing secured to the said sound producing housing and having a division wall therein, the said wall having a plurality of openings through it and a vibratory diaphragm closing each of said openings, each diaphragm having secured to one of its sides farthest from the said sound producing and intensifying means and extending transversely therefrom a plurality of pins of different lengths, a drive shaft rotatably mounted in the said motor housing and extending therefrom, a plurality of toothed wheels secured to the drive shaft in spaced apart relation and having their teeth engaged by the said pins secured to the said diaphragms, a second shaft rotatable in said motor housing having secured to it a plurality of vibratory diaphragm levers for controlling the vibrations of the diaphragms and means for turning the second named shaft to cause the said levers to press the diaphragms and dampen the vibrations thereof.
3. In a power generating apparatus comprising an impulse receiving circuit including means for producing sound and a housing for the said sound producing means, a motor housing secured to the said sound producing housing and having a division wall therein, the said wall having a plurality of openings through it and a vibratory diaphragm closing each of said openings, each diaphragm having secured to one of its sides farthest from the said sound producing means and extending transversely therefrom a plurality of pins, a shaft rotatably mounted in the said motor housing and extending therefrom, a plurality of toothed wheels secured to the drive shaft in spaced apart relation and having their teeth engaged by the said pins secured to the said diaphragms, a second shaft rotatable in said motor housing having secured to it a plurality of vibratory diaphragm levers for controlling the vibrations of the diaphragms and means for turning the second named shaft to cause the said levers to press the diaphragms and dampen the vibration thereof.
4. In a power generating apparatus compris-

ing an electromagnetic impulse receiving circuit including means for converting the said impulses received by said circuit into sound waves, a plurality of diaphragms arranged for intercepting the said sound waves emanating from said means for converting the electromagnetic impulses into sound, in combination with a rotatable shaft having a plurality of ratchets in spaced apart relation between its ends and mechanical means between said diaphragms and said ratchets for turning the ratchets by direct force of the vibrations of said diaphragms caused by the interception of the sound waves from said means for converting the electromagnetic impulses into sound waves.

5. In a power generating apparatus, a motor comprising a motor housing having a plurality of sound vibratory diaphragms secured therein, each of said diaphragms having associated therewith a plurality of pins, a drive shaft associated with the said diaphragms and having thereon between its ends a plurality of ratchets arranged to be rotated by the said pins, and means for controlling the vibratory movement of the said diaphragms.

6. In a power generating apparatus, a motor comprising a motor housing having a plurality of sound vibrated diaphragms secured therein, the said diaphragms having connected to each 30 a plurality of pins, a drive shaft associated with the said diaphragms and having thereon between its ends a plurality of ratchets arranged to be rotated by the said pins connected to said diaphragms.

35 7. In a power generating apparatus, a motor comprising a plurality of peripherally supported diaphragms in spaced apart relation, each diaphragm having extending from one of its sides a plurality of pins, a rotatable shaft in spaced relation to the said diaphragms, a plurality of ratchet wheels in spaced relation encircling the shaft between ends and engaged by the said pins.

8. In a power generating apparatus comprising a sound operable motor consisting of a plurality of vibratory diaphragms, a drive shaft, means associated with said diaphragms and said shaft for rotating the said shaft by vibrations of the diaphragms, and means consisting of a turnable shaft having thereon a plurality of 50 diaphragm vibration dampening members and means for turning the said shaft and dampening members to dampen the vibrations of said diaphragms.

9. In a power generating apparatus comprising a motor consisting of a vibratory diaphragm, a shaft and means associated with said diaphragm and said shaft for rotating the said shaft by vibrations of the diaphragms, and means consisting of a turnable shaft having thereon a diaphragm vibration dampening member and means for turning the said shaft to dampen vibrations of the diaphragm.

10. In a power generating apparatus comprising a sound operable motor consisting of a plurality of vibratory diaphragms, a drive shaft, means associated with said diaphragms and said shaft for rotating the said shaft by vibrations of the diaphragms, and means consisting of a turn-

able shaft having thereon a plurality of diaphragm vibration dampening members and means for turning the said shaft and dampening members to dampen the vibrations of said diaphragms, and means consisting of a turnable shaft, means for turning the shaft and means associated with the shaft for dampening the vibrations of the diaphragms.

11. In a power generating apparatus the combination comprising a motor including among its elements electromagnetic means for producing sound waves, a diaphragm vibrated by said sound waves directed thereto from said sound producing means, a frame between the sound producing means and said diaphragm for directing said sound waves to said diaphragm, a drive shaft, means for mounting the drive shaft for rotation, and a plurality of power impulse members operatively connected between said diaphragm and said drive shaft for delivering a succession of power impulses to the shaft in response to vibration of said diaphragm whereby continuous rotation of the drive shaft may be imparted thereto.

12. In a power generating apparatus, the combination which includes a housing, having extending therein a drive shaft, a diaphragm in said housing and vibratable by sound waves, a frame for directing sound waves to said diaphragm, and a plurality of power impulse members operatively connected with said diaphragm and said shaft for delivering a succession of power impulses to said shaft in response to vibration of said diaphragm whereby continuous rotation may be imparted to the said shaft.

13. In a power generating apparatus, an electromagnetic circuit, a sound operable motor having an enclosure, a plurality of sound vibratable diaphragms within said enclosure, the said diaphragms having associated therewith a plurality of driving members, a shaft mounted for forced rotation by said driving members and having ratchet-like members associated therewith for rotating the shaft by said driving members during vibration of said diaphragms by sound waves of audible frequency.

14. In a power generating apparatus, including a magnetic impulse electricity generating circuit, a sound operable motor having a housing, a plurality of sound vibratable diaphragms within said housing, the said diaphragms having associated therewith a plurality of driving members, a shaft mounted for forced rotation by said driving members and having ratchet-like members associated therewith for rotating the shaft by said driving members during vibration of said diaphragm by sound waves directed to said diaphragms.

15. In a power generating apparatus, an electromagnetic circuit, a sound operable motor having an enclosure, a sound vibratable diaphragm within said enclosure, the said diaphragm having associated therewith shaft rotating members, a shaft mounted for forced rotation by said shaft rotating members and having a ratchet-like member associated therewith for rotating the shaft by said shaft rotating members during vibration of said diaphragm by sound waves of audible frequency.

CHARLES W. DAKE.
